UNITED STATES PATENT OFFICE.

OMER CYPRIEN GOULET AND ARTHUR LAMARRE, OF FALL RIVER, MASSACHUSETTS.

LOOM-SIDE PROTECTOR.

No. 924,451.

Specification of Letters Patent.

Patented June 8, 1909.

Application filed August 18, 1905. Serial No. 274,734.

To all whom it may concern:

Be it known that we, OMER CYPRIEN GOULET and ARTHUR LAMARRE, citizens of the United States, residing at Fall River, 5 county of Bristol, and Commonwealth of Massachusetts, have invented certain new and useful Improvements in Loom-Side Protectors, of which the following is a specification.

10 This invention relates to the protection of cast iron frames and particularly to the protection of the castings which form the side of a loom. In this portion of a loom structure great difficulty is experienced 15 on account of the location in it of the box for the shaft and the necessity of tightening this box in the loom side. The box, which is usually located in an opening in the casting, is ordinarily held in place by 20 wedges and to tighten it these wedges are hammered between the casting and the box itself. This hammering has a tendency to crack the iron of the side, and in fact soon does crack it, and in a short time sufficiently 25 weakens the side so that it is necessary to replace the part with a new one. It is to prevent this breaking of the side and the loss and delay incident thereto that the present invention has been devised.

30 The invention is a clamping member adapted to support the frame against radial cracking and is provided with portions to support and secure the box and hold it tightly in place without the necessity of 35 wedges. The structure of this clamp will be more fully set forth in the specifications which follow and are shown in the drawings which form a part thereof and in which,

40 Figure 1. is an outside view of a frame with the protector in place. Fig. 2. is an inside view of the same. Fig. 3. is an edge view of a modified form of protector. Fig. 4. is a section on the line $x-x$, Fig. 2, and, 45 Fig. 5. is an inside view of the protector shown in Fig. 3.

A is a frame of any type and is merely indicated as a conventionalized form of the cast side frames usually employed on looms.

50 B is a box or journal for the shaft C.

D is the loom side protector consisting of

a plate E surrounded by an internal beveled rim F.

G is an inner rim rounded to correspond with the groove in the box B. which it supports.

H is a post which extends out from the plate E far enough to extend through the opening in the loom side. Its upper side has a surface h adapted to bear against the lug 60 b on the box B to press the box firmly against the upper part of the opening and bind it in place.

The post H terminates in a threaded stem I which is threaded to receive a nut K which 65 bears against the washer L. As indicated in Fig. 1 by the bolt head I¹ the stem I may be omitted and the post H bored so that the fastening can be put through as a separate bolt.

In Figs. 1 and 2 the protector is shown as integral but it is convenient in applying the protector under some circumstances to have it made in separate parts as indicated in Figs. 3 and 5. In these figures the parts 75 D¹ D² are provided with ears d which are held together by bolts d¹ and nuts d².

In applying the protector, if the loom is set up it is slipped on over the shaft, or if the two part protector is used, it is merely 80 bolted around it. The protector is then brought up to the frame and forced over the flange a of the frame A. The washer L is then applied on the inside and the nut K screwed on.

What we therefore claim and desire to secure by Letters Patent, is:

1. The combination with a plate forming a supporting frame having a flange extending therefrom and an opening surrounded by 90 said flange, of a securing plate having a rim extending from the edge thereof, said rim being adapted to envelop and engage the flange on the supporting frame, means carried by the securing plate for tightly holding a box in the opening, and means for clamping the securing plate in place on the supporting frame.

2. The combination with a plate forming a supporting frame having a flange extending therefrom and an opening surrounded by 100 said flange, of a diametrically divided

two part securing plate having a rim extending from the edge thereof and adapted to envelop and engage the flange on the supporting frame, means carried by the securing plate for tightly holding a box in the opening and means for clamping the securing plate on the supporting frame.

In testimony whereof, we have affixed our signatures in presence of two witnesses.

OMER CYPRIEN GOULET.
ARTHUR LAMARRE.
